UNITED STATES PATENT OFFICE.

JOHN V. CUNNIF, OF FALL RIVER, MASSACHUSETTS, ASSIGNOR TO JAMES K. LANNING, OF FALL RIVER, MASSACHUSETTS.

TOP-ROLL-SADDLE MECHANISM.

1,307,117.

Specification of Letters Patent. Patented June 17, 1919.

Application filed May 6, 1916. Serial No. 95,962.

To all whom it may concern:

Be it known that I, JOHN V. CUNNIF, a citizen of the United States, and a resident of Fall River, in the county of Bristol and 5 State of Massachusetts, have invented an Improvement in Top-Roll-Saddle Mechanism, of which the following description, in connection with the accompanying drawings, is a specification, like characters on the drawings representing like parts.

This invention relates to top roll saddle mechanism of various types.

In order that the principle of the invention may be readily understood, I have disclosed a single embodiment thereof in the accompanying drawings, wherein—

Figure 1 is a vertical sectional view of a top roll saddle mechanism embodying my invention;

20 Fig. 2 is a detail, partially in plan and partially in transverse section, of means for adjusting the weighted lever fulcruming member;

Fig. 3 is a vertical section of the construction shown in Fig. 2;

Figs. 4 and 5 are vertical sectional views of the upper drawing rolls and saddle members, and representing the weight-supporting member in different positions;

30 Fig. 6 is a view similar to Fig. 4, but representing a modified form of the invention;

Fig. 7 is a side elevation of one form of weight-supporting member;

35 Fig. 8 is a vertical section of the weighted member shown in Fig. 7; and

Fig. 9 is a similar view, the upper part being broken away, of a slightly modified form of the weighted member.

40 While my invention may be applied to various types of top roll saddle mechanism, I have herein represented it as applied to the same type thereof that is disclosed in my Patent No. 1,072,317, dated September 2, 1913.

Referring more particularly to the drawings, the front pair of drawing rolls is represented at 1, 1', the intermediate pair at 2, 2', and the back pair at 3, 3'. Said rolls may 50 be of the usual or any other suitable construction and may be supported upon a standard 4 that is itself mounted upon the spinning frame or roller beam 5.

While I may employ one or more saddle members of any suitable or usual construc-

tion, I have herein represented a front saddle member 6 supported upon the front drawing roll 1 and a rear saddle member 7 supported upon the intermediate and back drawing rolls 2, 3.

60 In top roll saddle mechanisms as heretofore constructed, a weight strap or weight-supporting member has been employed, and means have been provided to adjust the same with respect to the saddle members.

65 I have disclosed improved means for adjusting the weight strap or weight-supporting member herein indicated at 8, and have provided means whereby the effective weight may be applied over the axes of any one 70 of a plurality of the said drawing rolls, that is, above the point or zone of engagement of an upper drawing roll and corresponding lower drawing roll or at intermediate points therebetween, without bringing said weight- 75 supporting member into contact or objectionably near the drawing rolls.

In the drawing and spinning of yarns, it is important that the proper pressure be applied to the various rolls in order to draw 80 and spin the proper counts and in order to provide a uniform or substantially uniform yarn. In accomplishing these and other objects, I have in the disclosed embodiment of the invention provided the upper 85 end of the weight-supporting member with a deflected portion 9, preferably having a transverse rib or tooth 10 at its under side adapted to take into any desired one of a series of transverse notches 11 in the saddle 90 member, or one of said saddle members if a plurality be employed. I have herein represented the front saddle member 6 as suitably notched for this purpose.

95 In Fig. 1, I have represented the toothed end of the weight-supporting member as engaging the saddle member at a point between the axial lines of the front and intermediate drawing rolls. It will be evident from said figure that there is a wide range of 100 adjustment of said weight-supporting member, and that as shown in Fig. 4 the weight thereof may be applied directly above the axial line of the intermediate drawing member without bringing the weight-supporting 105 member objectionably near the intermediate drawing rolls. By turning the weight-supporting member through 180° as illustrated in Fig. 5, the weight of said supporting member 8 may be applied directly above the 110

axial line of the front drawing rolls or at an intermediate point between the front and intermediate rolls, as shown in Fig. 5.

It is evident that in this manner and by a very simple construction, I secure an extended range of adjustment of the weight-supporting member. In Fig. 6, I have shown a slightly modified form of my invention. Therein the weight-supporting member 8 is provided at its upper end with a laterally extending hub 12 tapped into which is a threaded bolt 13 having in one end a transverse slot 14 by which it may be adjusted. The head 15 of the bolt is preferably provided with a relatively sharp circumferential edge 16 to engage any one of a series of notches 11 of the front saddle member 6. By this means, I secure a compound or double adjustment, namely, that of the weight-supporting member with respect to the bolt 13 and that of the said bolt with respect to the saddle member. I have herein represented the weight-supporting member 8 as having an opening 17 at or near its upper end through which the saddle member 6 is adapted to pass. The lower end of said weight-supporting member is provided with a vertical slot 18 for the reception of the weight lever 19. Said weight lever has applied thereto the usual weight 20 and is fulcrumed within the loop or bracket 21. I have herein in dotted lines in Fig. 8 represented the weight-supporting member 8 as having a deflected lower end 22, by means of which, if desired, the point of engagement of said weight-supporting member and the weight lever 19 may be in line with the point of application of the weight of the weight-supporting member 8 to the saddle member 6.

Heretofore so far as I am aware, the loop or bracket for the weight lever 19 has been vertically adjusted. I have discovered that it is of marked importance that the loop or bracket be adjustable in the same direction as the weight-supporting member 8; that is to say, transversely of the spinning frame or roller beam 5. While this result may be effected in any suitable manner, I have in Figs. 1, 2 and 3 represented the said loop or bracket as threaded in or otherwise secured to the hub 22 of a bracket 23, the latter being provided with an elongated slot 24 for the reception of a screw 25. The spinning frame or roller beam 5 is provided with a transverse slot 26 of suitable extent for the reception of the hub 22 and permitting the transverse adjustment of said hub and of the bracket 23 by means of the slot 24 and screw 25. In this or in any other suitable manner, the loop or bracket 21 may be adjusted coincidently with the adjustment of the weight-supporting member 8.

65 I have demonstrated from the practical

operation of my invention that I may draw and spin a more even yarn than heretofore, which may be either light or heavy and of any desired number.

From the foregoing description, it will be evident that I have provided means whereby the proper pressure may be applied to the desired drawing rolls or proportioned between the drawing rolls, thereby to effect the drawing and spinning of any desired count of yarn and the formation of a uniform yarn.

Having thus described one illustrative embodiment of my invention, I desire it to be understood that although specific terms are employed, they are used in a generic and descriptive sense and not for purposes of limitation, the scope of the invention being set forth in the following claims.

Claims:

1. A top roll saddle mechanism comprising a front saddle, a back saddle, and a weight supporting member having a deflected upper end provided with a tooth like formation to engage a similar formation upon one of said saddles. 85

2. A top roll saddle mechanism including a saddle member and a weight-supporting member having a deflected upper end to engage said saddle member and shiftable therewith, said saddle member and deflected upper end having interengaging toothed formations. 95

3. A top roll saddle mechanism comprising a saddle member and a weight-supporting member having a deflected upper end to engage said saddle member and shiftable therewith, said deflected upper end being provided with a tooth to engage a similar formation upon the saddle member. 100

4. A top roll saddle mechanism comprising a saddle member and a weight-supporting member having a deflected upper end which may be positioned in either of two opposite directions, thereby to apply a weight thereof directly above the axes of either of two upper drawing rolls. 110

5. A top roll saddle mechanism comprising a saddle member, and a weight-supporting member having an integral formation which may be positioned so as to apply the weight thereof directly above the axes of either of a plurality of upper drawing rolls. 115

6. A top roll saddle mechanism comprising a saddle member, three pairs of drawing rolls, and a weight-supporting member having a deflected upper end adapted to be positioned so as to apply the weight thereof directly above the middle drawing roll. 120

7. A top roll saddle mechanism comprising a saddle member, and a weight-supporting member having an integral deflected upper end for applying the weight thereof at a point removed from the plane of the body of said member, said weight support- 125

ing member having on said deflected upper end a tooth to engage and adjustable along a toothed formation extending along the saddle roll.

5 8. A top roll saddle mechanism comprising a saddle member, a weight-supporting member 8, means whereby the upper end of said member 8 may engage the saddle member at any one of a plurality of points there-
10 along, a fulcruming member 19 for the weight-supporting member, the lower beam 5, an upstanding bracket 21 operatively connected to the fulcruming member 19, and means for adjusting the bracket 21 trans-
15 versely of the roller beam.

9. A top roll saddle mechanism comprising a saddle member, a weight-supporting member 8, a fulcruming member 19, the roller beam 5, an upstanding bracket 21 opera-
20 tively connected to said fulcruming member 19, a bracket 23 supporting said bracket 21,

and slot and screw provisions for adjusting said bracket 23.

10. A top roll saddle mechanism comprising a saddle member, a weight supporting 25 member 8 having a deflected upper end adapted to be turned in either of two opposite directions to engage the saddle member, a fulcruming member 19 for the weight sup-
30 porting member, the roller beam 5, an up-
standing bracket 21 operatively connected to the fulcruming member 19, and means for adjusting the bracket 21 transversely of the roller beam.

In testimony whereof I have signed my 35 name to this specification in the presence of two subscribing witnesses.

JOHN V. CUNNIFF.
